UNITED STATES PATENT OFFICE

LYMAN L. JONES, OF SEATTLE, WASHINGTON, ASSIGNOR TO AMERICAN CAN COMPANY, OF NEW YORK, N. Y., A CORPORATION OF NEW JERSEY

AIR TESTER

Application filed February 2, 1927. Serial No. 165,296.

This invention relates to pneumatic testers for tin cans and other metal containers, and has for its object broadly the provision of a can tester that will operate with certainty and accuracy independently of the air pressure available for the testing.

In the manufacture of tin cans, it is the usual practice to include in each line of can body making machinery an automatic testing device for determining the perfection of the seams of the finished can bodies. These machines receive the cans as they arrive in processional order and after temporarily sealing the open ends inject air under pressure. The cans subjected to this internal air pressure are carried throughout a predetermined path of travel and the perfection of the seams determined by the maintenance of the pressure of air within the can. When the air pressure is diminished while the cans are thus sealed, the cans are considered imperfect and are sorted from the perfect cans by devices automatically controlled by the condition of the cans themselves.

Generally in the past, the detecting and separating control has required that a uniform air pressure be employed, the detectors usually operating because of a fall from an absolute and predetermined pressure. For example, assuming that the pressure applied to a can is 20 pounds, the tolerance usually allowed is merely an ounce or two, and any less pressure registered by the devices results in the removal of the can from the usual subsequent line of feed. If, however, the pressure applied to the cans be less than that allowed by this tolerance, all of the cans having this lesser pressure will be thrown out, and if there be more than the 20 pounds pressure applied the leaks are not detected.

My invention contemplates, and has for its principal object, the provision of a detector or can tester control device which will operate on pressure differences as contradistinguished from a departure from an absolute and predetermined pressure condition.

The invention has for a further object the provision of a can tester and a detector therefor which will operate as well at low pressures as at high pressures, and without re-

quiring special adjustment of the parts for the purpose.

Another important object of the invention is the provision of a device of this character consisting of few and simple parts unlikely to require frequent repair, replacement or adjustment, and which in every way will be capable of accurate use under commercial conditions.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a can testing apparatus in which my present invention is embodied;

Fig. 2 is a similar view taken from the opposite side of the apparatus;

Fig. 3 is an enlarged elevation of a can testing unit, a portion of the rotating disc being shown in section;

Fig. 4 is a view partially in section through a detector control and valve;

Figs. 5, 6 and 7 are enlarged sections through the contact cap, showing the parts in various relations;

Fig. 8 is a section taken substantially on the line 8—8 of Fig. 12;

Fig. 9 is a detail view of the detector control parts being shown in section;

Fig. 10 is a top plan view thereof;

Fig. 11 is an enlarged top plan view of the same, with the insulating cap removed;

Fig. 12 is a section taken substantially on the line 12—12 of Fig. 8; and

Fig. 13 is a section taken substantially on the line 13—13 of Fig. 12.

Reference character 20 indicates a base of a usual commercial can tester supported upon legs 21 and carrying uprights 22 having bearings 23 for the cross-shaft 24 of the can tester disc 29, which is driven in any usual or preferred fashion, the driving mechanism not being shown on the drawings. An upright frame 25 is connected by cross bars 26 with the uprights 24 and provides sup-

port for the can receiving chute 27 and delivering mechanism 28.

The disc 29 is provided with a number of bosses 32 (Figs. 3, 4 and 8), upon which are mounted can tester pockets. Each boss 32 is perforated centrally and a valve stem 33 of a valve and control 34 extends therethrough and engages a head plate 37 recessed at 38 to receive a cushioning member 39 (Fig. 8), preferably pneumatic, against which the open end of the can body 30 is thrust. The bottom end 31 of this body is engaged by a clamp plate 40 carried by a threaded stem 41 (Fig. 3) in turn engaged with an arm 42 of the sleeve 43 slidably mounted upon a hollow shaft 44 fastened in a double bearing 45 through the disc 29.

A body holder 126 is also mounted on the sleeve 43 and extends into position to hold the can body 30 when it is thrust into the testing apparatus and until it is clamped in place. The sleeve has an arm pivoted at 125 to a link 124, in turn pivoted at 123 to a longitudinal sliding bar 121 movable in a boss 122 on the disc and carrying at its end a roller 120 arranged in a cam guideway 119.

Air is admitted to the can shortly after it is clamped in position from a central air admission and shutoff device 51 located adjacent the center of the disc, which control is suitably ported and receives air under pressure through a conduit 52 and delivers the exhaust back through a conduit 53. Pipes 50 communicate with the valves 34, a said pipe and valve being provided at each can testing pocket.

The valve 34 comprises a body 47 (Fig. 8) having air ducts 65 and 67' leading, respectively, into the valve housing and through the stem into the can. The pipe 50 is connected to the valve housing by a short pipe 48 and elbow 49 (Fig. 10).

A detector or can control is provided for each pocket and this is threaded into a recess 54 in the top of the housing 47. The detector comprises a flange 56 threaded into the recess and engaging upon the upper side of a diaphragm 57, the other side of which is in contact with the bottom of the recess. An opening 66 forms communication between the recess and the duct 67' and through the duct with the interior of the can 30.

A sleeve or hollow housing 55 extends up from the flange 56 and accommodates a spring 61 bearing against a flange 62 at the upper end of the housing 55 and upon a washer 63 at the diaphragm, said washer encircling the end of a stem 59 which passes through the diaphragm and is engaged by a nut 60.

A cap 74 of electrically non-conducting or insulating material is screwed on the upper end of the sleeve 55 and carries at its top a fixed electrical contact 75. When air is admitted to the interior of the can, the di-

aphragm is pressed upwardly correspondingly against the force of the spring 61, and the stem 59 of the diaphragm is provided with movable contacts of special construction and arrangement at its upper end. The upper end of the stem is in the form of a plate 67, in which two converging grooves 68 of tapered form are provided (see Figs. 5 to 11). Two slide electrical contacts 69 are mounted in these grooves and these are held in friction engagement therewith by an anchor plate 70, which is pressed against them by a spring 72 (Fig. 11) about a bolt 71 extending through the head 67 of the stem and engaged by a nut 73.

The slide contacts are of such length that when no air is present at the diaphragm, the lower ends are engaged by the flange 62 of the housing 55, thus arranging the slide contacts in initial predetermined position. When pressure is admitted to a can held in the pocket, the diaphragm is raised and the two slide contacts thrust into engagement with the fixed contact 75. This engagement moves the contacts along their slideways 68, arranging them in the slideways in accordance with the degree of deflection of the diaphragm, in turn in accordance with the force of the pressure. The diaphragm is, of course, pressed from its seat until the pressure in the can is in balanced relation to the force of the spring 61, and any diminution of the pressure thereafter results in a corresponding return movement of the diaphragm.

Since the slide contacts 69 are frictionally held in the stem head, they move with the diaphragm in this movement and are instantly disengaged from the contact 75. This disengagement is, therefore, independent of the departure from an absolute degree of pressure within the can and wholly dependent upon the variation after a predetermined relation is assumed commensurate with the initial pressure. Furthermore, since the friction on the slide contacts 69 must be overcome before the said contacts move in their slideways 68, a fine adjustment for a predetermined size of leak can be made by adjusting this friction on the contacts by turning or moving the bolt 71 and thus changing the tension of the spring 72.

Figs. 5 and 6 illustrate the effect upon the sliding contacts and different pressures in the can; and

Fig. 6 shows an arrangement of slide contacts for a pressure in the can greater than that provided in the arrangement shown in Fig. 5.

A control plate 76 (Figs. 8, 12 and 13) is arranged upon a cross piece 26 and carries an electric contact plate 77 secured thereto as follows: An insulating plate 78 is fixed on the control plate 76 and a shoulder bolt 79 extends through a bushing 80 therein. This bolt is engaged with one end of the contact 130

plate 77, and a spring 81 presses the plate away from the insulation. An electric wire 90 is connected to this plate 77. As each can pocket is brought by the rotation of the wheel 5 adjacent the position of discharge, the contact plate 77 is engaged by the fixed contact 75, and if the can has not leaked, the slide contact 69 will complete a ground connection and through it an electric circuit, as will now be described, reference being had particularly to Fig. 12;

The slide contacts are grounded at 89 (Fig. 12). The wire 90 leads from contact 77 to a battery 91, and from this wire 92 connects to 15 a solenoid 93 in turn grounded at 94. This magnet is provided with an armature adapted to control the delivery of the cans in accordance with their condition. This is accomplished by the arrangement of a delivery gate 20 control member provided at each can pocket.

The shaft 44 associated with each can pocket is hollow and a rod 82 is arranged through it and extends out from each end thereof. This rod is provided with two lock 25 grooves 86 and 87, into either of which a lock plunger 83 is frictionally pressed by a spring 84 in a cap 85. Each rod 82 is arranged before it arrives adjacent the plate or arm 76 with the lock plunger 83 in the groove 87, 30 this being accomplished by a suitable cam 88 on the upright 22. Thus arranged, the adjacent end of the rod is adapted for engagement by a shifting member 96 of the plate 76 when a leaky can is contained in the pocket. 35 This shifting member is pivoted at 95 and has a rounded head 97, which is pressed into the path of the end of the rod 82 by a plunger 100 arranged in an opening 101 in the plate 76 and pressed out by a spring 101'. When a 40 perfect can is present in a pocket, the end of the rod may freely depress the plunger against the force of the spring. An obstruction 103 normally is interposed in the path of a shoulder 102 on the deflector member 96 45 and this obstruction is withdrawn only when a perfect can is in the pocket passing this station. When, however, a leaky can passes the obstruction remains in operative position, and the rod is thrust to the right (viewing Fig. 50 13) moving into the position there disclosed with the lock plunger 83 in the groove 86. If the circuit is completed to the electromagnet by the presence of a perfect can, the obstruction 55 pivoted at 104 is moved out from under the shoulder 102 on the deflector member, permitting the depression of the deflector member 96.

The lever 103 is normally held in obstructing position by an armature stem 105 about 60 which is arranged spring 107 (see Fig. 12) and completion of the circuit by the maintenance of contacts engagement in the control withdraws the obstruction.

The delivery mechanism 28 comprises two 65 delivery chutes 117 and 115. A gate 114 is

pivoted at 113 and normally forms a continuation of the floor 116 and chute 117, which gate in its normal position closes chute 115.

An arm 112 is fixed on the pivot 113 of the gate 114, and this arm is connected by link 70 111 with a swinging arm 110 pivoted at 109 on a bar 26. A spring 118, pulling upon the arm 110, holds the gate 114 to maintain the chute 117 in normally open relation, i. e. in position for the reception of a perfect can. 75

When, however, an imperfect can arrives at the delivery point with the rod 82 thrust out in the position shown in Fig. 13, it engages a cam 108 rigid with the arm 110, and moves this cam in a clockwise direction, as 80 shown in Fig. 2, swinging the arm 110 correspondingly and lifting the gate to open the mouth into the chute 115 for the defective can.

It is thought that the invention and many 85 of its attendant advantages will be understood from the foregoing description, and it will be apparent that various changes may be made in the form, construction and arrangement of the parts without departing from 90 the spirit and scope of the invention or sacrificing all of its material advantages, the form hereinbefore described being merely a preferred embodiment thereof.

I claim:

1. In a pneumatic can tester, the combination of a succession of can carriers, means confining air under pressure in cans carried in said carriers, and a device detecting difference in pressure occasioned by leaks through 100 out a predetermined path of travel comprising an element which is moved by the pressure of air within the can, means controlled by the movement of said element for variously delivering leaking and non-leaking cans, 105 and means whereby said element of the detector is readjusted upon release of said air pressure in the can.

2. In a pneumatic can tester, the combination of a can carrier, means supplying air 110 under pressure to the interior of the can when sealing the same, a detector communicating with the interior of the can and having a diaphragm and parts moved by said diaphragm and relative to said diaphragm 115 and brought to an initial reference position by the air pressure in the can and independently of the amount of said pressure, said detector parts being movable from said initial reference position upon diminution of the 120 pressure in the can through leakage, and devices controlled by the movement of said parts for variously delivering leaking and non-leaking cans.

3. In a pneumatic can tester, the combination of a can carrier, means supplying air under pressure to the interior of the can when sealing the same, a detector communicating with the interior of the can and having 125 parts brought to an initial reference posi- 130

tion by the air pressure in the can and independently of absolute amount of said pressure, said detector parts being movable from said initial reference position upon diminution of the pressure in the can through leakage, and devices controlled by the movement of said parts for variously delivering leaking and non-leaking cans, said detector parts automatically assuming a predetermined initial position upon release of the air pressure in said cans.

4. A pneumatic can tester, comprising, a diaphragm subjected to and movable in accordance with the degree of air pressure applied within the can and changes thereof, fixed and movable electric contacts, a connection between the movable contacts and said diaphragm adapted to bring said movable contacts into engagement with the fixed contact upon initial pressure in the can, said connection automatically altering its relation with respect to the movable contacts in accordance with the initial pressure in the can, and moving said contacts thereafter out of engagement with the fixed contact upon diminution of pressure within the can.

5. A control for a pneumatic can tester, comprising a diaphragm, a fixed electrical contact, movable contacts having a predetermined inoperative position and a predetermined path of movement therefrom into engagement with said fixed contact and actuated by said diaphragm into engagement with said fixed contact upon the application of initial pressure within the can, said movable contacts disengaging said fixed contact upon movement of the diaphragm upon diminution of pressure in the can.

6. A control for a pneumatic can tester, comprising a diaphragm adapted to be deflected by the pressure applied in the can, a fixed electrical contact a stem carried by the diaphragm and movable toward said fixed contact as the diaphragm moves when pressure is applied to the can, and movable contacts carried by said stem and arrangeable thereupon in accordance with the pressure in the can and in engagement with the fixed contact, said stem and movable contacts moving together with the diaphragm away from said fixed contact upon diminution of the pressure in the can.

7. A control for a pneumatic can tester, comprising a diaphragm with a face of which the interior of the can may communicate, a fixed electrical contact, movable electrical contacts associated with said diaphragm and automatically arrangeable in relation thereto in accordance with the pressure in the can and moving with said diaphragm upon diminution of pressure in the can and out of contact with said fixed contact, and means whereby said movable electrical contacts are adjusted in position relative to the diaphragm.

8. A control for a pneumatic can tester, comprising, a diaphragm subjected to the pressure in the can, a fixed electrical contact, a movable electrical contact controlled by said diaphragm and assuming a predetermined can testing relation therewith when air pressure is first admitted to the can and in engagement with the fixed contacts, the relation between said movable contact and said diaphragm being thereafter fixed to cause separation of said movable and fixed contacts upon diminution of pressure in the can.

9. A control for a pneumatic can tester, comprising a diaphragm chamber open to the pressure applied to the can, a diaphragm therein, a stem engaging said diaphragm and extending outwardly therefrom, a housing surrounding said stem, a head on said stem, sliding moving contact members in said head, a fixed contact in the end of said housing against which said movable contacts are engaged, said fixed contacts sliding said movable contact to a predetermined can testing position, said movable contacts separating from said fixed contact upon initial movement of the diaphragm as a result of diminution of pressure in the can.
